ENVELOPE BANDING MACHINE

Lewis C. Pearce, Berea, Ohio, assignor to Pearce Development Company, Cleveland, Ohio, a corporation of Ohio

Filed Jan. 14, 1957, Ser. No. 633,912

26 Claims. (Cl. 53—198)

This invention relates to envelope banding machines. It is an object of this invention to provide a machine adapted to have a plurality of single envelopes placed in the machine and having means to automatically form packages of envelopes of a predetermined number and to form a sealed band of tape around the formed package of envelopes.

It is a further object of the invention to provide an envelope banding machine having means to form packages of a predetermined number of envelopes and to form a band around the center of the formed packages, and in which means are further provided to adjust the band forming means to envelopes of varying widths and heights whereby the band is formed centrally of the envelope packages.

It is a further object of the invention to provide an envelope banding machine having an envelope storage magazine with means to count the envelopes out of said magazine one by one and having transfer means to transfer said counted out envelopes from said magazine to a banding station, said transfer means being operated in synchronism with said counting means, whereby said transfer means goes through a transfer cycle once for each time a predetermined number of envelopes is counted out of said magazine.

A yet further object of the invention is to provide an envelope storage magazine with counting means for continuously counting out envelopes from said magazine one by one and advancing means in said magazine for urging said envelopes towards said counting means, said advancing means being synchronized with said counting means.

A further object of the invention is to provide an envelope banding machine with an envelope storage magazine, means to count said envelopes out of said magazine, and means to form said counted out envelopes into a package adjacent to said magazine, whereby said package may then be transferred to a banding station.

Still another object is to provide vacuum operated means for pulling envelopes from a storage magazine, and means responsive to the failure of the vacuum operated means to pull an envelope to shut off the machine.

Another object of the invention is to provide an envelope banding machine with means to encircle packages of envelopes with a sealing tape, and means to feed a supply of tape to said encircling means whereby the tape is fed freely as the packages are encircled, and means to clamp the tape taut around the packages.

A still further object is to provide an envelope banding machine with means to encircle a package of envelopes with a sealing tape, and tape feeding means to form a slack loop of tape to be fed to the encircling means, the tape feeding means being synchronized with the encircling means to form the slack loop of tape just before such tape is needed to encircle a new package of envelopes.

Another object of the invention is to provide an envelope banding machine having an envelope storage magazine mounted on a first frame, transfer means mounted

2

on a second frame for transferring a predetermined number of envelopes in a group to a banding station, and in which said second frame is transversely adjustable relative to said first frame, whereby different widths of envelopes may be handled, and banding and sealing means mounted on a third frame to form a band around said group of envelopes, said third frame being carried by and vertically adjustable relative to said second frame to accommodate envelopes of different heights.

10 A further object of the invention is to provide an envelope banding machine with an envelope storage magazine, means to count envelopes out of said magazine one by one, transfer means to carry a predetermined number of counted out envelopes from said magazine, and a disappearing stop means to hold said counted out envelopes in readiness for said transfer means, said disappearing stop means being synchronized with said transfer means to withdraw from holding envelope position when said transfer means operates to carry said envelopes from said magazine.

15 Another object of the invention is to provide a tape sealing means having a heated portion adapted to heat seal a tape, a cooling means to cool said tape, and a knife means to sever the sealed tape intermediate the sealed portion of said tape.

20 A still further object of the invention is to provide an envelope banding machine having an envelope storage magazine with means to continuously count out envelopes from said magazine one by one, transfer means to carry a predetermined number of envelopes from said magazine to a banding station, means at said banding station to encircle said envelopes with a band of tape, and means to seal said encircled tape, and in which said counting means, said transfer means, and said encircling and sealing means are all operated from a common continuously operating power drive source, and further in which said transfer, encircling and sealing means all complete a single cycle of operation in the time said counting means counts out a predetermined number of envelopes.

25 40 Other objects and advantages will become apparent in the course of the following detailed description.

In general, there are three principal stations in the machine, the first being the storage or magazine station, generally indicated on Fig. 6 by the letter A, the second is the counting station, indicated by the letter B, and the third is the banding station, indicated by the letter C.

Also generally speaking, the machine includes five synchronously operating mechanisms for performing the specific functions of the machine, although these mechanisms are integrated with necessary auxiliary mechanisms to effect the complete operation of the machine.

The first of these mechanisms is the magazine at the station A, into which envelopes may be fed or stacked, either manually or mechanically. This magazine includes an envelope feeding mechanism which continuously urges the stacked envelopes longitudinally and horizontally of the machine toward the counting station B.

The second of the operating mechanisms is the counting mechanism at station B, which operates continuously to count out envelopes from the magazine one by one, so that a package of envelopes of the desired number is formed, and to condition the package so that it may be operated upon by the third of the operating mechanisms, which is the transfer mechanism, positioned generally intermediate the counting station B and the banding station C.

This third, or transfer, mechanism removes the package of envelopes from the counting station B, and moves the package as a unit into a position whereby the package may be banded together at the banding station.

The fourth mechanism, at the banding station C, operates to form a band of tape around the package, and then seals the band of tape and cuts the sealed band so that the package is complete.

The fifth mechanism is the tape feeding mechanism which operates to unroll ribbon of banding tape from a supply roll in intermittent steps, the periodicity of these steps being in synchronization with the cycling of the banding mechanism, so that tape may be freely applied to the packages of envelopes as the tape is encircled around the envelope package by the banding mechanism.

In order that the inter-relationship of the various mechanisms of the machine may be made more clear,

reference is now made to Figs. 4 and 4A. These figures illustrate in a diagrammatic fashion the manner in which the various mechanisms of the device are all driven from a single power source so that they will operate in synchronism with one another.

All of the mechanisms of the machine are connected to be driven by a single main drive motor 9 coupled by drive belt 10 to pulley 11 mounted on shaft 12. Bevel gear 13, fixed to shaft 12, is in driving engagement with bevel gear 14, fixed to shaft 16, to drive gears 17 and 18, fixed thereto.

Gear 18 is in meshing engagement with gear 19, mounted on shaft 21. Cam 22 is fixed to one end of shaft 21, which also carries gear 23, and a set of cams 24 at the other end thereof.

As cam 22 rotates, it imparts a reciprocatory motion to link system 26, to impart a ratchet drive to double pulley 27. This latter pulley is connected by drive belts to drive pulleys 28 and 29. Pulley 28, fixed to shaft 31, will thus drive the two bevel gears 32 and 33, fixed to shaft 31. Bevel gear 32 is in meshing engagement with bevel gear 34 fixed to shaft 36, which carries bevel gear 37 at the other end thereof, this latter gear being in meshing engagement with bevel gear 38, mounted on roller 39 to provide a drive for one of the vertical feed belts 41. Similarly, gear 33 is in driving engagement with bevel gear 42, shaft 43, bevel gear 44, bevel gear 46, roller 47 to drive the other vertical feed belt 48.

The other pulley 29, driven by double pulley 27, is fixed to shaft 51 to provide a drive for the horizontal feed belt drive roller 52 and the horizontal feed belts 53 driven thereby.

Returning to camshaft 21, gear 23, fixed thereto, is in driving engagement with gear 54, to drive worm gear 56 fixed to the envelope advancing, or counting, wheel 57.

Also driven by shaft 16, through gear 17 fixed thereto, is idler gear 58 fixed at one end of shaft 59, and gear 61, fixed to the other end thereof. Drive is transmitted through intermeshed gears 62 and 63 to drive shaft 64, having three drive gears, 66, 67 and 68 fixed thereto.

Drive gear 67 transmits its drive through intermeshed gears 69 and 71 to shaft 72 which carries the kick-out cam 73 at the other end thereof.

Drive gear 68 is in driving engagement with gear 74, fixed to camshaft 76. Cam 77, mounted on end of camshaft 76, operates to provide a reciprocatory motion to gear segment 78, in mesh with gear 79, fixed to shaft 81, so that this shaft is provided with an oscillating movement during operation of the machine. This movement is transmitted through bevel gears 82 and 83, shaft 84, bevel gears 86 and 87 to the upper shaft 88.

A set of cams 89 is fixed to the other end of camshaft 76 to provide a drive source for the envelope transfer mechanism, to be later described.

Drive gear 66, fixed to shaft 64, is in driving engagement with bevel gear 91, fixed to the universal drive shaft 92, carrying bevel gear 93 at the other end thereof, to transmit rotational movement through the intermeshed bevel gear 94, fixed to shaft 96. Bevel gears 97 and 98 transmit rotational motion to shaft 99 having the sealing wheel 101 mounted thereon.

A first cam 102 is mounted on shaft 96 to impart a vertical reciprocatory motion through link system 103 to rack 104.

A second cam 103, also mounted on shaft 97, imparts a reciprocating movement through rack 109, pinion gear 111 and rack 112, to provide a reciprocatory movement to the envelope holding means 113 (not shown on this figure).

This same cam 108 also imparts a reciprocatory movement to rack 114, to thereby oscillate pinion gear 116 and shaft 117. A second pinion gear 118 carried on shaft 117 imparts a reciprocatory movement to rack 119.

Referring to Fig. 4A, a friction disc assembly 121 is also mounted on shaft 117 to impart a reciprocatory

movement through links 122 and 123 to tape brake shoe 124.

Having now shown in general how the power drive sources for the various mechanisms of the machine are interrelated, the operation of each of the mechanisms of the machine may now be described in detail.

The magazine feeding mechanism

The magazine, indicated generally in Figs. 2, 3 and 8 by the letter A, includes an elongated horizontal trough 150, extending longitudinally of the machine. This trough 150 is of rectangular cross-section and is formed of a bottom wall 151, a fixed outer side wall 152, and a laterally adjustable side wall 153. The lateral spacing between the side walls is adjusted to be slightly greater than the length of the envelopes 154 to be packaged. By adjusting the position of the side wall 153, envelopes of various sizes may be accommodated.

It is intended that the envelopes be stacked or fed into the trough 150 in an upright condition. To feed the envelopes toward the counting station B, endless feed belts 53 are provided which are mounted on transverse horizontal rollers 52 and 52a. The upper flights 53a of these feed belts overlie the bottom wall 151 to engage the bottom edges of the envelopes stacked in the trough to feed the same forwardly toward the counting station B.

To aid the belts 53 in feeding the envelopes, a pair of endless feed belts 41 and 48 are arranged on opposite sides of the trough in advance of station B, to engage the opposite sides of the envelopes and effect the final feed thereof to the counting station. The belts 41 and 48 are driven intermittently at a speed sufficient to maintain an ample supply of envelopes at the counting station and to urge them forwardly at that point.

As seen in Figs. 5 and 2, belt 41 is mounted on two rollers 39 and 39a. Roller 39 is journaled on shaft 156 which is fixed to a transversely adjustable support plate 157. A cap nut 158 prevents the roller 39 from riding up on the shaft 156, and thus keeps the bevel gear 30, fixed to roller 39, in meshing engagement with bevel gear 37. Roller 39a is mounted for free rotative movement on shaft 159, which is also mounted on support plate 157.

A belt backing plate 161 is disposed in back of the envelope-contacting portion of belt 41, the plate 161 being slidably mounted for vertical movement on support 162, in turn fixed to the movable support plate 157. The backing plate 161 carries thereon two laterally extending pins 163 and 164, disposed above and below the feed belt 41. If it is desired to change to an envelope of a different height, the belt 41 may be moved upwardly or downwardly by sliding the backing plate 161 in a corresponding direction on support 162, and the pins 163 and 164 will force the belt 41 to move upwardly or downwardly on the rollers 39 and 39a, so that the final height of the belt 41 above the bottom wall of trough 150 will be approximately in the center of the envelope.

The backing plate 161 extends beyond roller 39a, forming two parallel extension arms 161a and 161b, with the central portion cut out along the line 161c to allow the belt 41 to pass around the roller 39a. These extension arms serve as a vertical guide to the envelopes once they have passed the roller 39a under the drive of the feed belt 41.

The other feed belt, 48, is mounted in a similar manner, on rollers 47 and 47a, with a backing plate 166 mounted for vertical movement on support 167 fixed to the frame of the machine.

The side wall 153 of trough 50 and feed belt 41 are adjustable transversely of the machine in the following manner. As has been stated, these elements are mounted on a support plate 157, and thus if this plate is moved transversely of the machine, the width of the trough 150 may be adjusted to receive different widths of envelopes therein. The support plate 157 has fixed thereto three

transversely extending racks 168a, 168b and 168c. In meshing engagement, one to each rack, are three pinion gears 169a, 169b and 169c, all fixed to a common shaft 171 mounted in bearings 172a, 172b and 172c. The shaft 171 has a manually operable handle 173 fixed thereto, whereby rotation of the handle will simultaneously rotate the pinion gears 169a, 169b and 169c, to move the racks 168a, 168b and 168c equally to maintain the parallel relationship of the side walls 152 and 153 of the trough 150 as the side wall 153 is moved by the racks. The bevel gear 32, which provides the drive for feed belt 41, is adapted to move longitudinally of shaft 31, as the bevel gear 32 has an internal key (not shown) which rides within the longitudinal keyway 31a formed in shaft 31. Thus, as the adjustable side wall 153 is moved, the bevel gear 32 will slide longitudinally on shaft 31 without an interruption in the drive between shaft 31 and gear 32.

As has been pointed out above, both of the two feed belt systems obtain their drive from a double pulley 27 which is driven by a reciprocating link mechanism 26 engaged by cam 22 mounted on drive shaft 21. The manner in which this drive is delivered to the feed belts is illustrated in Fig. 3. Cam 22, mounted on shaft 21, engages the vertical link 176 which has its upper end pivotally connected to link 177 having its other end pivotally mounted on the frame 5 of the machine. The lower end of link 176 is secured to one end of the horizontal drive rod 178, the other end of which carries a pivot support member 179. Link 181, having its upper end loosely mounted on pulley shaft 182 fixed to the frame of the machine, is pivotally connected at its lower end to the pivot support member 179. Spring 183 constantly urges the drive rod 178 to the right, as seen in Fig. 2. Link 181 carries a ratchet arm 184, spring biased into engagement with ratchet teeth 186 mounted on pulley 27. In operation, the cam 22 will force the drive rod to the left on each rotation of shaft 21, and this movement will force the link 181 to pivot around the pulley shaft 182 in a clockwise direction. This motion will cause the ratchet arm 184 to force the engaged ratchet teeth 186 attached to pulley 27 in a clockwise direction. When the drive rod 178 returns to the right under the force of spring 182, the ratchet arm 184 will ride over the ratchet teeth 186 to engage another one of said teeth for the next cycle of operation. This intermittent drive of pulley 27 is transmitted by belt 187 to pulley 28, and by belt 188 to pulley 29, and then to the horizontal and vertical feed belts 53, 41 and 48. As will be seen, this intermittent operation of the feed belts is synchronized to the removal of envelopes from the magazine, and thus the amount of rubbing of the feed belts against stationary envelopes is largely eliminated, which would otherwise be present if the envelopes were held against forward motion while the feed belts continually moved to urge the envelopes in the forward direction.

The counting mechanism

The mechanism for counting the envelopes from the magazine is shown in Figs. 5 and 8. In general, the machine is provided with a pair of sucker rods which alternatively fasten themselves by vacuum suction to the leading envelope in the magazine and pull the envelope forwardly to a position whereby, after a predetermined number of envelopes has been so moved, they may be carried as a unit to the banding station. Assisting the sucker rods is a helical counting wheel which, through its rotation, permits only one envelope to be advanced at a time by the sucker rods.

The sucker rod 201, shown in Fig. 5 as extending longitudinally of and underneath the envelope magazine 150, is provided at its right end with a sucker head 202. This head has a passage 203 therethrough to which a flexible tube 204 is attached from a source of vacuum to

provide vacuum for the sucker head. The passage 203 terminates on the face 206 of the sucker head so that when the sucker head is moved upwardly into engagement with an envelope 154, the envelope may cover the passage 203 and the vacuum in the passage will hold the envelope to the sucker head so that a rightward movement of the sucker head will pull the envelope with it.

The left end of the sucker rod 201 has a sliding fit through a support block 207, mounted for pivotal movement on shaft 208 fixed to the frame 5 of the machine. A washer 209 mounted on shaft 208 spaces the support block 207 from the support block 207a of the other sucker arm 201a. The left end of sucker arm 201 terminates in a roller 211 engaged by a block 212, mounted on lever 213. The lever 213 is pivotally mounted on shaft 214 fixed to frame 5 of the machine and has a forward extending portion 216 terminating in a roller 217, this roller being held against cam 218 of cam group 24 under the force of spring 219.

The right end of the sucker arm 201 is provided with a bracket member 221 fixed to the sucker arm by screw 222. Tension spring 223 extends from the support block 207 to the bracket 221 to urge the sucker arm 201 in a leftward direction so that the sucker arm roller 211 is in constant engagement with the lever block 212.

In operation, as shaft 21 rotates, cam 218 will force the lever 213 to oscillate about the pivot shaft 214, thus imparting a reciprocating motion to the sucker arm 201, to move this arm to the right and then to the left once for each rotation of shaft 21.

This movement to the right of the sucker arm will pull an envelope from the magazine. For the sucker arm to return to pick up another envelope, it is necessary that the sucker head move downwardly below the envelope before it may return. This is accomplished in the following manner. The sucker arm bracket 221 has pivotally connected thereto a link 224, the lower end of this link being pivotally connected to link 226, pivotally mounted on shaft 214. Spring 227, fixed to link 226 and pin 228 of frame 5, urges link 226 in an upward direction. Link 226 also carries a cam follower 229 held by spring 227 against cam 231 of cam group 24.

Thus, as shaft 21 rotates, cam 231 and cam follower 229 cause the link 226 to oscillate around pivot shaft 214, and link 224 imparts an upward and downward reciprocatory movement to sucker arm bracket 221. The cams 218 and 231 are designed so that a full cycle of movement of the sucker head 202 is from left to right on a constant level in contact with the envelope, then downwardly below the envelope, leftwardly below the bottom of the envelope just moved and then upwardly to engage a new envelope.

A second sucker arm 201a is mounted for identical movement by elements corresponding to the elements described above and being designated by the same reference numbers, with the subscript "a" appended thereto. The two sucker arms 201 and 201a are operated by their respective cams 218, 231 and 218a, 231a, so that the two sucker arms are 180° out of phase with one another. This enables one sucker arm to be moving one envelope to the right while the second sucker arm is moving leftwardly underneath the moving envelope into a position to engage the next envelope.

As the envelopes 154 are fed in the magazine past the feed rollers 39a and 47a they are arrested from further forward motion by coming into engagement with the counting wheel 57, whose shaft 236 is mounted longitudinally below the magazine. The counting wheel shaft 236 has fixed thereto a worm gear 56 by which a rotative drive is imparted upon the wheel 57, through idler gear 54 in meshing engagement with gear 23 mounted on shaft 21.

The counting wheel 57, more fully illustrated in Figs. 16 and 17, has a rear face 237 against which the en-

velopes are urged by the feed belts 41 and 48. The wheel 57 has a quarter section removed, as at 238, with the leading edge 239 being provided with a forwardly inclined cam face 241, and the trailing edge 242 being provided with a rearwardly inclined cam face 243, so that the wheel 57 has a helical action as it rotates.

The manner of operation of the counting wheel 57 may best be explained in reference to Fig. 8. The sucker head 202 is synchronized to the rotation of the counter wheel so that the sucker head will be in engagement with an envelope and just starting to pull the envelope from the magazine when the leading edge 239 of the wheel is slightly below the bottom edge of the envelope. The trailing edge 242 of the wheel will be in contact with the envelopes to prevent their forward movement, and the sucker arm will pull on the first envelope in the magazine sufficiently so that the leading edge of the wheel will enter between the envelope being pulled by the sucker head 202 and the next envelope. Continued rotation of the wheel will free the first envelope in a peeling manner, for unimpeded movement by the sucker head, while the remaining envelopes will be held in place by the rear face 237 of the wheel. The sucker arms 201 and 201a are operated by the same drive shaft 21 as is the counting wheel 57 and thus the operations of these elements are easily synchronized to one another. Since for each rotation of the drive shaft 21 each sucker arm moves through a complete cycle, the wheel 57 must rotate twice for one rotation of the drive shaft 21, to allow one envelope to be counted out of the magazine by the wheel under the influence of each sucker arm. As explained previously, the drive shaft 21 is driven by drive shaft 16, in turn directly related to the main belt drive of the machine. As the machine is in operation, envelopes are fed from the magazine at a constant rate determined by the rotation of the main drive shaft 16 and its gear relation to drive shaft 21.

The envelopes 154, as they are urged forwardly by the feed belts 41 and 48, pass under the upper guide member, indicated generally at 245, which is adjusted to be but slightly spaced above the top of the envelopes 154. The support guide member 245 has a plurality of longitudinally disposed guide bars 246, each mounted on a transverse carrier arm 247, the latter being fixed to a vertically adjustable carriage 248 mounted for vertical sliding movement on the upright member 249 of frame 5a. Carriage 248 has an internally threaded element 251 fixed thereto through which the threaded adjustment rod 252 extends. The upper end of the adjustment rod is supported in collar 253 (Fig. 6) mounted on frame member 249 to permit rotative movement of the adjustment rod without vertical movement thereof. A manually operable handle 254 fastened to the rod enables an operator to rotate the rod to move the carriage 248 upwardly and downwardly, as desired.

Each guide bar 246 is provided with a stop member 256 to hold the top of the envelope as they are counted out of the magazine, as illustrated in Fig. 5, and thus prevents them from falling forwardly before they are carried to the banding station.

Further included in the counting mechanism is the auxiliary vacuum valving mechanism. As each sucker head is in contact with an envelope for only about a quarter of its cycle of operation, it is necessary to provide a valve arrangement to limit the application of suction to such times as the sucker head passage 203 is blocked by an envelope. This is provided as follows. A valve port plate 257 is loosely mounted on drive shaft 21, so that the drive shaft may rotate freely therethrough. Pin 258 mounted on valve port plate 257 passes through frame member 5 of the machine to hold the valve port plate against rotation with shaft 21 while yet allowing a limited longitudinal movement on shaft 21. The valve port plate 257 has a first set of passages therethrough, 261 and 262, each terminating at the left face of the plate

263 as seen in Fig. 8. Passage 261 is connected at one end to the flexible tube 204 leading to the sucker head 202, and passage 262 is connected at one end to conduit 264 which is adapted to be connected to a source of vacuum (not shown). Similarly, passages 261a and 262a are provided in valve port plate 257, passage 261a being connected to flexible tube 204a and thus to sucker head 202a, and passage 262a being connected to conduit 264a and thus to the source of vacuum.

Fixed to shaft 21 is the slide valve member 266, having a face 267 in rotative sliding contact with face 263 of the valve port plate 257. The valve member 266 has a groove 268 formed on the face 267, enabling the valve port passages 261 and 262 to be placed in communication with each other when both passages are in registration with the groove 268. Similarly, on further rotation, the groove 268 will serve to place passages 261a and 262a in communication with each other. Compression spring 269 forces the valve port plate 257 into firm contact with valve member 266 to prevent air leakage between the contacting faces thereof.

As the valve member 266 rotates on shaft 21, vacuum will be applied alternately to the sucker head flexible tubes 204 and 204a, the length of such application being determined by the length of groove 268, and the vacuum will be applied to the sucker heads 202 and 202a for the period in which they move envelopes from the magazine. Valve member 266 is positioned on shaft 21 so that vacuum is applied to the sucker heads as they first come into contact with the envelopes to be moved.

In addition, means are provided to shut off the machine in case the vacuum applied to the sucker heads is interrupted, as, for example, if the magazine runs out of envelopes, or if the sucker heads cannot move an envelope from the magazine. Two pressure responsive switches 271 and 271a are provided, as illustrated in Fig. 19. Switch 271a is connected by conduit 272a to conduit 264a leading to the source of vacuum. The vacuum in conduit 264a communicates through conduit 272a to the lower chamber 273a of switch 271a, and will cause diaphragm 274a to flex downwardly against the bias of spring 276a to carry the bridging contact bar 277a, fixed to the diaphragm, out of engagement with the switch contacts 278a and 279a. If at any time the vacuum in the lower chamber 273a fails, spring 276a will force the diaphragm upwardly, allowing the contacts to be shorted by the contact bar 277a.

Pressure-responsive switch 271 is connected by conduit 272 to conduit 264 in the same manner, and operates in the same manner as pressure-responsive switch 271a.

Microswitches 281 and 281a are also provided, and positioned to be engaged by cam 282, mounted on drive shaft 21. Cam 282 is positioned on drive shaft 21 so that it will close microswitch 281 during the period when vacuum will be applied through conduit 264 to sucker head 202, as explained above, and cam 282 will close microswitch 281a during the period when vacuum will be applied through conduit 264a to sucker head 202a.

Terminals 279 and 279a of the pressure-responsive switches 271 and 271a are electrically connected together to one terminal 283 of a voltage source. Terminal 278 is connected through microswitch 281 to one side of a solenoid 284, and terminal 278a is connected through microswitch 281a to the same side of solenoid 284, the other side of the solenoid being connected to the other terminal 286 of the voltage source. The main drive motor 9 is also connected to the voltage source terminals 283 through a normally closed switch 287 which is adapted to open if the solenoid actuator 284 is energized, and the main drive motor 9 is also connected to the other voltage source terminal 286.

When motor 9 is energized from terminals 283 and 286, shaft 21 will be driven so that cam 282 will alternately close the microswitches 281 and 281a. Under normal operating conditions, a vacuum will be applied to

conduits 264 and 264a to cause the pressure-responsive switches 271 and 271a to assume an open circuit position. If the machine is operating properly, vacuum will be applied to the sucker heads 202 and 202a only when such heads are covered by an envelope, and thus the vacuum will not be broken. If for some reason one of the sucker heads does not engage an envelope when vacuum is being applied to the sucker head, as for example sucker head 202, air will enter the sucker head 202 and be drawn through passage 203, tube 204, valve port plate passage 261, valve member groove 268, valve port passage 262, into conduit 264, and into chamber 273 of pressure-responsive switch 271 to cause this switch to close. At the same time, cam 282 will close the microswitch 281 and a complete circuit will be made to energize solenoid 284 which then opens switch 287 to deenergize the drive motor, and shut off the machine.

Thus, if for any reason one of the sucker heads 202 or 202a fails to pick up an envelope while forming a package to be banded, the machine will automatically stop, so that envelope packages containing less than the desired number of envelopes will not be formed.

The transfer mechanism

25 In general, the transfer mechanism operates in synchronization with the counting mechanism, just described, to carry a predetermined number of envelopes from the constantly advancing series of envelopes being counted from the magazine. Referring to Fig. 4, the transfer mechanism is operated, as has been explained, from cam-shaft 76, driven by drive shaft 64, which, in turn, is driven in synchronization with the main drive shaft 16 through the gear train 58, 61, 62 and 63. The transfer mechanism will go through a complete cycle for a single revolution of camshaft 76, and the number of envelopes transferred by this mechanism will be dependent upon the number of revolutions of camshaft 21 which counts the envelopes out of the magazine, to each revolution of cam-shaft 76. This number of revolutions of camshaft 21 may be varied by changing the gear ratios of gears 61, 62 and 63 which couple the drive shafts 16 and 64 together.

For example, each full revolution of camshaft 21 (which actuates the sucker rods) will count two envelopes from the magazine. If it is desired to band the envelopes into packages of six envelopes, the gear train 61, 62 and 63 is chosen so that camshaft 76 will rotate through a single revolution during the time camshaft 21 rotates through three revolutions. In this manner, each cycle of operation of the transfer mechanism will pick up the six envelopes counted from the magazine during the cycle of the transfer mechanism. If it is desired to change the number of envelopes in the packages, this may be done by merely changing the overall gear ratio between the drive shafts 16 and 64, so that the desired number of envelopes will be counted out of the magazine during the time it takes for the transfer mechanism to perform a complete cycle of operation.

The transfer operation is effected in two stages, with 60 the envelopes being first moved from adjacent the envelope magazine to an intermediate position, and then being carried from this position to the banding station.

The mechanism for moving the envelopes from the envelope magazine to the intermediate position is best 65 illustrated in Figs. 5, 9, 13 and 15. In general, as illustrated in Fig. 15, a picker bar 301 is provided to operate in synchronization with the counting mechanism so that it will rise up from a lower position as shown in Fig. 5, to pick off the envelopes which have been pulled from the 70 magazine by the sucker rods. At the same time that the picker bar 301 is raised, the clamp bar 302 pivots in a counterclockwise direction to clamp the package of envelopes between the picker bar and the clamp bar. The picker bar is then caused to rotate in a clockwise direction 75 to carry the clamped envelopes to the dotted position

shown in Fig. 15. The picker bar 301 is then lowered below the bottom of the envelopes and rotated in a counterclockwise direction to the position as shown in Fig. 5 to complete the cycle. The manner in which this motion is effected will now be described.

The initial transport mechanism may be best seen in Fig. 13 representing an exploded view of the working parts, and Figs. 15 and 5 illustrating the same parts in their assembled relationship.

Picker bar 301 is fixed at its lower end to shaft 303 pivotally mounted in parallel links 304 and 304a. The other ends of these links are fixedly mounted on shaft 306 which is rotatably mounted on frame 5a. Shaft 306 also has fixedly mounted thereon crank arm 307 pivotally connected by link 308 to lever arm 309. This lever arm is rotatively mounted on shaft 311, fixed to frame 5a, and has a pin 312 to which tension spring 313 is attached to provide an upward bias to the lever arm, and a cam follower 314. The lever arm 308 is also shown in Fig. 14 in operative relationship to cam 89c mounted on cam-shaft 76.

Cam 89c effects the up and down movement of the picker bar 301 in the following manner. As the cam 89c rotates in a continuous clockwise direction from the position shown in Fig. 14, the cam follower on lever arm 309 will move upwardly under the influence of spring 313, to cause the crank arm 307 to rotate shaft 306 in a clockwise direction. This motion will cause the links 304 and 304a to pivot in a clockwise direction, forcing shaft 303 and the attached picker bar upwardly. As the cam 89c continues to rotate, cam follower 314 will be forced downwardly and the crank arm 307, shaft 306 and links 304 and 304a will rotate in a counterclockwise direction to lower the picker bar 301 to its original position. The picker bar 301 will thus move vertically through one cycle of upward and downward movement for a single revolution of cam 89c.

The picker bar shaft 303 has crank arm 316 fixed thereon, carrying link 317 pivotally mounted thereon. Crank arm 316 also has an angle bracket 318 fixed thereto, enabling compression spring 319 to be inserted between link 317 and the bracket 318. Link 317 is provided with a generally square block 321 pivotally mounted thereon at its upper end, the block 321 being adapted to slide vertically within the channel 322 of bracket 323.

Bracket 323 has two holes 324 and 324a therethrough to receive pins 326 and 326a mounted on the upper ends of lever 327 and link 327a, respectively.

Link 327a is pivotally connected at its lower end to the frame 5a, and lever arm 327 is freely and pivotally mounted intermediate its ends to the clamp bar shaft 328, this shaft being rotatively mounted in frame 5a. Affixed to the lower end of lever arm 327 is a cam follower 329 held against cam 89b by tension spring 331. Cam 89b is mounted on the same camshaft 76 as is cam 89c.

In operation of the machine, as illustrated in Fig. 13, the cam 89b will be rotating in a clockwise direction, and cam follower 329 will be moved leftwardly against the bias of spring 331 to cause the lever arm 327 to pivot about shaft 328 in a clockwise direction. Pin 326 will thus move the bracket 323 to the right, the bracket being held in a horizontal position by link 327a. Block 321, riding in bracket channel 322, will cause the crank arm assembly 316 and 317 to rotate in a clockwise direction. As the picker bar shaft 303 is fixed to the lower end of crank arm 316, the rotation of the crank arm will be transmitted to shaft 303 and thus to the picker bar 301 fixed thereto, to rotate the picker bar to the dotted position of Fig. 15.

Continued rotation of cam 89b will cause the spring 331 to move the lever arm 327 back to its original position, to return the picker bar to its original leftward position.

Thus, cam 89c will cause the picker bar 301 to move vertically up and down for each rotation of cam 89c, and

cam 89b will cause the picker bar 301 to move horizontally to the right and then to the left, for each rotation of cam 89b. The combined action of these two cams thus causes the top of the picker bar 301 to describe a roughly rectangular path.

Spring 319 in crank arm assembly 316, 317 allows some play of the picker bar 301 as it comes to the dotted position shown in Fig. 15. If the picker bar 301 is held stationary at the dotted position, as for example by a thick package of envelopes, the forced rightward movement of bracket 323 will be taken up by spring 319 of the picker bar crank arm 316.

As has been stated, the clamp bar 302 moves against the envelopes held by the picker bar, as illustrated in Fig. 15, so that the package of envelopes may be pulled from the stop member 256 of the upper guide bars 246. The manner in which the clamp bar is operated will be now described, again with particular reference to Fig. 13.

Mounted for free rotative movement on clamp bar shaft 328 is lever arm 336, having cam follower 337 held against cam 89a by the force of tension spring 338. Crank arm 339 is fixed to shaft 328 and has a forwardly extending lip 341 to engage one end of compression spring 342, the other end being held against the upper end of lever arm 336.

In operation, as cam 89a, also mounted on camshaft 76, rotates in a clockwise direction, spring 338 will cause cam follower 337 to move rightwardly to engage the flat side of cam 89a, to cause the lever arm 336 to pivot in a clockwise direction, in turn exerting through compression spring 342 a rotative force to crank arm 339, moving the clamp bar shaft 328 and clamp bar 302 fixed thereto, in a counterclockwise direction to clamp the envelopes. Spring 342 is of a lesser strength than spring 338 and permits some relatively free play of crank arm 339 in relation to lever arm 336 to enable the clamp bar 302 to adjust to different thicknesses of envelope packages.

The picker bar 301 is bifurcated at its lower end to form two legs 301a and 301b through which the clamp bar 302 extends, so that the clamp head 343 will be prevented from lateral movement with respect to the picker bar 301.

As the picker bar 301 moves rightwardly, the clamp bar 302 moves in conjunction with the picker bar so that the package of envelopes is clamped therebetween during such movement. As the clamp bar 302, fixed on shaft 328, is fixed against any but rotative movement to the frame 5a, the clockwise rotation of the clamp bar 302 causes the clamp head 343 to move gradually downwardly, so that at its rightward limit of travel, as shown in dotted line in Fig. 15, the clamp head 343 is below the bottom of the envelopes, so that they may be moved to the banding station C. Continued rotation of cam 89a will then return the clamp bar to the initial position, as shown in Fig. 5.

Thus, the combined actions of the picker bar 301 and clamp bar 302 serve to move the counted out envelopes from the magazine to the intermediate position shown in dotted line in Fig. 15. At this point the envelopes are held against forward movement by coming to rest against lower stop member 351 rigidly connected to lower crank arm assembly 352, and against the upper stop member 351a rigidly connected to the upper crank arm assembly 352a. Crank arm assembly 352 is fixed on shaft 81 for oscillatory movement induced by the rotation of cam-shaft 76, and crank arm 352a is fixed on shaft 83 for oscillatory movement also induced by cam-shaft 76.

As best illustrated in Fig. 10, cam 77, mounted on camshaft 76, is positioned to engage cam follower 353, mounted on pin 351, fixed to the lower portion 78a of gear segment 78, which is pivotally mounted on shaft 356 fixed to frame 5a. Tension spring 357 is provided to hold cam follower 353 in contact with cam 77. The upper portion 78b of gear segment 78 is pivotally

mounted on pin 354, with tension spring 358 being provided to hold the upper and lower portions 78a and 78b of gear segment 78 normally in alignment.

As cam 77 is rotated by camshaft 76, in a counter-clockwise direction as viewed in Fig. 10, the gear segment 78 will rotate in a clockwise direction about shaft 356 to impart a counterclockwise rotation to gear 79 and shaft 81. This will give a clockwise rotation to shaft 81, as seen in Fig. 5, to rotate the lower crank arm assembly 352 in a clockwise direction from the initial position shown in Fig. 5 (or the dotted position of Fig. 15) to a final position shown in solid lines in Fig. 15. At the same time, the shaft 88, connected by gear 87, shaft 84, gear 83 and gear 82 to shaft 81, will turn in a counterclockwise direction, as seen in Fig. 5, to rotate the upper crank arm assembly 352a from the initial position shown in Fig. 5 (or the dotted line position of Fig. 15) to the final position as shown in Fig. 15.

During such rotation of the lower and upper crank arm assemblies 352 and 352a, the crank heads 361 and 361a will engage the envelopes, which were moved to rest against the stop members 351 and 351a, to force the envelopes to the final banding position. The crank heads also push the envelopes past the stop members 351 and 351a so that the crank arm assemblies will clear the envelopes on the return stroke. The crank arm assemblies are returned as their shafts 81 and 88 are reversed in rotation as gear segment 78 returns to its original position under the engagement of cam 77 with cam follower 353.

The upper crank arm assembly 352a, shaft 88, gear 87 and gear 86 are all carried by the vertically slideable carriage 248, so as to be adjustable for envelopes of different heights. Gear 86, which drives the upper crank arm assembly shaft 88, is loosely mounted on shaft 84, and carries a pin 362 riding in groove 363 formed longitudinally of shaft 84, to allow the gear 86 to slide vertically on drive shaft 84 while maintaining a drive connection therebetween.

Also included in the transfer mechanism is the kick-out mechanism. In general, this mechanism is provided to hold the package of envelopes being formed until the initial transfer mechanism, i.e. the picker bar 301 and clamp bar 302, moves the package, the kick-out mechanism being removed to allow the package to be moved and being returned to hold the next package as it is formed.

As seen in Fig. 4, the kick-out camshaft 72 is driven through gears 71, 69 and 67 by the same drive shaft, 64, that drives the transfer mechanism camshaft 76. The kick-out cam 73, mounted on the kick-out camshaft 72, may be best seen in Figs. 6 and 1. The kick-out cam 73 is formed in the shape of a single flight helix to which cam follower 366, mounted on lever arm 367, is held in contact by spring 368. The lever arm 367 is pivotally mounted at its lower end 369 to the frame 5 of the machine, while its upper end is pivotally connected to the kick-out bar 371. This bar extends generally transverse of the machine with spring 372 being provided to apply a retarding pressure to the package of envelopes being formed by the counting mechanism.

In operation, the kick-out bar 371 is normally in the dotted-line position in Fig. 1, in engagement with the envelopes being counted out of the magazine (see also the dotted-line position in Fig. 5). The kick-out cam will rotate in a counterclockwise direction, as seen in Fig. 6, and with the cam follower 366 held in engagement with the cam. When the outwardly inclined portion of the kick-out cam 73 engages the cam follower 366, the lever 367 and kick-out bar will begin to move outwardly toward the full-line position shown in Fig. 1, until the kick-out bar 371 is completely out of engagement with the envelopes. As the cam 73 continues to rotate, the cam follower will ride off of the inclined helical portion

of cam 73 to snap the kick-out bar back to its initial position.

The operation of the kick-out bar 371 is synchronized to the operation of the picker bar 301 so that the picker bar 301 will move the package of envelopes forwardly at the time that the kick-out bar is in the full-line position of Fig. 1, with the kick-out bar being returned to its dotted-line position immediately after the picker bar 301 has moved the package of envelopes forwardly, past the kick-out bar.

As has been explained and as shown in Fig. 4, the three major elements of the transfer mechanism, i.e. the picker bar 301 and clamp bar 302, the lower and upper crank arm assemblies 352 and 352a, and the kick-out bar 371, are all operated by their common drive shaft 64. This enables these three transfer mechanisms to be easily and positively synchronized, one to another, by the proper fixing of the operating cams, cams 89a, 89b and 89c for the picker bar and clamp bar, cam 77 for the crank arm assemblies and cam 73 for the kick-out bar, to their respective camshafts.

It is desirable that the transfer mechanism thus described be positioned with respect to the envelopes being transferred so that the transfer mechanism will operate generally intermediate the side edges of the envelopes. Thus, as different widths of envelopes are operated upon, it is necessary to provide means whereby the transfer mechanism is adjustable transversely of the machine.

As has been explained, the picker arm 301, clamp arm 302 and the upper and lower crank arm assemblies 352 and 352a are all mounted on frame member 5a, whereas the envelope magazine station A is mounted on frame member 5. As seen in Figs. 5 and 6, frame member 5a is mounted for transverse movement on frame 5 in the following manner. Two transverse guide members 376 and 376a are rigidly fixed to frame 5 to support frame 5a, and are received between downwardly depending lugs 377 formed in frame 5a to prevent relative longitudinal movement between frames 5 and 5a, while allowing relative transverse movement therebetween.

The externally threaded adjustment screw 378 has one end rotatably mounted in frame 5 so as to prevent longitudinal movement of the screw 378 with respect to the frame, and a manually operable handle 379 is provided to enable an operator to rotate the screw. The other end of the adjustment screw passes through an upstanding and internally threaded portion 381 of frame 5a (Fig. 10). As the adjustment screw is rotated, the upstanding portion 381 of frame 5a will be advanced along the adjustment screw 378, to move the frame 5a transversely of the frame 5 on the transverse guides 376 and 376a.

As has been explained, camshaft 76, which operates the transfer mechanism, receives its drive from gear 68, mounted on drive shaft 64. Gear 68 is mounted on drive shaft 64 so as to allow longitudinal movement of the gear along drive shaft 64 as frame 5a is adjusted transversely of frame 5. Frame 5a is provided with upright stanchions 382 and 383 forming a bearing support for gear 74, mounted on camshaft 76, and these stanchions also encompass both sides of gear 68 to maintain gears 68 and 74 in meshing engagement with each other. Drive shaft 64 is provided with a longitudinal groove 384, into which pin 386, fixed to gear 68, is received. As frame 5a is moved transversely of frame 5, the stanchions 382 and 383 will force gear 68 to slide longitudinally of the drive shaft 64, with the gear pin 386 riding in the drive shaft groove 384 to provide a driving engagement therebetween.

Gear 67 on drive shaft 64, which provides the drive for the kick-out mechanism, is not affected by transverse adjustment of frame 5a, as it is not desired to change the position of the kick-out arm with different width of envelopes.

The sealing mechanism

In transferring the package of envelopes to the final

banding station C, the envelopes are forced forwardly against a vertically disposed ribbon of tape so that the package of envelopes in the final position will have the ribbon of tape extending vertically on the forward side of the package. The sealing mechanism then operates in general to set in motion a pair of opposed jaw members to clamp the free ends of the tape around the package of envelopes, and a heat sealing wheel then seals the portion of tape held between the jaws.

The tape joint is then cooled and severed intermediate the ends of the sealed portion so that the now sealed package is free of the tape, and so that the free ends of the tape are joined together to receive the next package of envelopes.

As shown on Fig. 1, the power drive for the jaw and sealing mechanism is obtained from bevel gear 66, fixed to drive shaft 64, in mesh with bevel gear 91, rotatively mounted in frame 5, and fixed to one end of the universal drive means 92. The universal drive means 92 has a first member 401, fixed to bevel gear 91 by a universal joint 402, and a second member 403, fixed to bevel gear 93 by a second universal joint 404. A sleeve 406 surrounds the two members 401 and 403 and carries pins 407 and 408 which slide within grooves 409 and 411 longitudinally formed in universal members 401 and 403, respectively, to hold members 401 and 403 against relative rotation.

Bevel gear 93 is journaled for rotation in bracket 412, fixed to frame 5b, and is in mesh with bevel gear 94 mounted on shaft 96 journaled in frame 5b. As may be seen, drive power is transferred from drive shaft 64 to drive shaft 96 by the preceding drive connection while yet allowing a relative motion of frame 5b to frame 5 in a horizontal or vertical direction. Gear ratios are chosen so that drive shaft 96 will rotate at the same speed of rotation as does camshaft 76 of the transfer mechanism.

Referring to Fig. 10, the means for operating the opposed jaw members of the device may now be described.

Drive shaft 96 has fixed thereto cam 102 in engagement with cam follower 413 mounted on lever assembly 414. This lever assembly is provided with a central cut-out portion 416 in which is slidably mounted a pivot pin bearing 417. Cap screw 418 enables the bearing 417 to be fastened to the lever assembly 414 at different positions so that the lever arm distance from the bearing 417 to the cam follower 413 may be adjusted. Pivot pin 418 passes through the pivot pin bearing 417 to pivotally mount the lever assembly on bell crank lever 419, pivotally mounted intermediate its ends by pin 421 to frame 5b. Compression spring 422 is mounted in abutment with the lower end of lever 419 and an upright projection 423 of frame 5b. The provision of spring 422 and lever 419 enables the pivot pin 418 to be moved so that if the ordinary clockwise rotation of the lever assembly 414 is prevented by an inability of the right end of the lever assembly to move, the cam 102 acting against the cam follower 413 will cause the pivot pin 418 to move upwardly against the face of compression spring 422.

The right end of lever assembly 414 is pivotally connected at 424 to link 426 in turn pivotally connected at 427 to rack member 104. (See also Fig. 21). Rack member 104 slides in a vertical channel 428 formed in the upright member 249 fixed to frame 5a, and is in engagement with pinion gear 106 mounted on shaft 424 fixed to frame 5b. Pinion gear 106 is also in meshing engagement with a second rack member 107, mounted for a vertical reciprocating movement in a vertical channel 431 in the upright member 249 of frame 5.

With the above assemblage of elements, it may thus be seen that a rotation of drive shaft 96 will cause the lever assembly 414 to oscillate around the pivot pin 418 to cause the rack 104 to move in a reciprocating motion. The movement of rack 104 will be transmitted through pinion gear 106 to cause rack 107 to move in a recipro-

catory manner equal and opposite to the movement of rack 104.

Rack member 104 has fixed thereto at its upper end a horizontally extending arm 432 carrying the upper jaw member 433 at its outer end (Fig. 9). Rack member 107 has attached thereto the lower jaw members 434 and 436. As the rack 104 moves downwardly and the rack 107 moves upwardly, the upper jaw 433 will close to meet jaw members 434 and 436, as shown in Fig. 9.

The upper jaw member 433, shown in Fig. 5, comprises two outside plates 437 and 438 carrying therebetween a spacing block 439. Block 439 is provided with an internally recessed portion 441 to receive a screw 442 for vertically reciprocating movement. Screw 442 is secured to the vertically movable jaw shoe 443 and compression spring 444 places a downward bias on jaw shoe 443 with respect to the spacing block 439.

Jaw member plate 438 is bifurcated at its lower end at 438a and 438b to allow the sealing tape to pass therebetween, the plate 438 being internally recessed at 438c to mate with the internally recessed portion 434c of lower jaw member 434. The lower jaw member 434 is similarly bifurcated at 434a and 434b to enable the sealing tape to pass therebetween. Thus, as the upper and lower jaw members 433 and 434 close together, the bifurcated portions thereof will overlap at the recessed portions 438c and 434c thereof, with the sealing tape being held between the overlapped portions of the jaw members.

In a similar manner, the upper jaw member plate 437 and lower jaw member 436 are formed so that they will close in the same overlapping fashion, with the sealing tape being held between the bifurcated, overlapped portions thereof.

The two lower jaw members 434 and 436 are spaced laterally from one another so as to allow the sealing wheel 101 to rotate therebetween.

In operation of the machine, cam 102 forces lever assembly 414 to pivot and move rack 104 downwardly and rack 106 upwardly, so that the upper and lower jaw members carried thereby will close. Further movement of the jaws and racks is not possible, and the continued rotation of cam 102 forces the bell crank lever 419 to pivot against the bias of compression spring 422, and the spring 422 is thus utilized to provide the closed pressure between the upper and lower jaw members.

Returning to Fig. 10, shaft 96 has mounted thereon cam 108, in back of cam 102, and shown more fully in Fig. 11. It is through this cam that the actuation of the envelope holding finger means 113 is obtained.

A link 446 is pivotally mounted at 447 to frame member 5b, and carries at its lower end at 448 a cam follower 449 held in engagement with cam 108. A Z-shaped link 451 is pivotally mounted intermediate its ends on link 446 at 448, and is pivotally fixed at its left end to link 452 also pivotally mounted on frame member 5b. Coiled spring 452a interconnects the pivot juncture of links 451 and 452 with frame member 56, thereby maintaining cam follower 449 against cam 108.

A bridge member 456, fixed to uprights 454 and 453 of frame member 5a, carries a depending channel member 457 having a channel 458 adapted to receive a sliding block member 459.

Upright members 453 and 454 of frame 5a are notched at their upper ends to receive an actuating bar 456 for reciprocating longitudinal motion therein. Bar 456 is provided with depending channel member 457 having a channel 458 to slidably receive block member 459 pivotally mounted at 448 on the lower end of link 446. By this arrangement, the rotary motion of cam 108 will induce a reciprocating longitudinal movement of actuating bar 456, while allowing the frame member 5b to be vertically moved with respect to frame member 5a. A horizontal bridge member 461 fixed to upright members 453 and 454 serves to keep the actuating bar 456

in the notches formed in the upright members 453 and 454.

Fixed to the left end of the actuating bar 456 is rack 109, in mesh with a double pinion gear 111 mounted on bridge member 461, the pinion gear 111 also being in meshing engagement with a second rack 112.

Referring also to Fig. 5, the operation of the envelope-holding means 113 may now be explained. The envelope-holding means 113 is pivotally mounted at 462 to frame member 5a, and is normally biased to a dotted-line position, as shown in Fig. 5, by means of spring 463. As the rack 109 moves to the right, pin 464 on rack 109 engages the envelope-holding means 113 to pivot it in a clockwise direction, to the position shown in Fig. 11. The arcuate finger projection 466 will thus hold the bottom edge of the envelopes out of the way of the bottom jaw member 436 as it moves upwardly. The bottom jaw member 436 has a cam surface 467 attached thereto to engage a stop member 468 secured to shaft 462 to prevent the envelope-holding means 113 from reTRACTING to its dotted-line position of Fig. 5, even though the rack 112 has been returned to its position as there shown, until the bottom jaw member is lowered. This prevents in a positive manner any chance that the arcuate finger 466 will interfere with the sealing wheel 101.

As has been partially explained, the sealing wheel 101 is mounted on a drive shaft 100 journaled for rotation in frame 5b, in such a manner that the wheel 101 rotates between the two lower jaw members 434 and 436. The sealing wheel drive shaft 100 obtains its rotative movement through intermeshed bevel gears 99 and 98 from drive shaft 96.

The sealing wheel 101, as shown in Fig. 18, has mounted therein an electrical heating unit 471, energized through wires 472 extending through the wheel shaft 100 to a conventional commutator means 473. The heating unit 471 thus heats the leading surface of the wheel 101 to heat seal the sealing tape, the tape being then cooled as the wheel 100 continues to rotate. A plurality of holes 474 are formed in the remainder of the sealing wheel 101 to enable the heat from the heating unit to be quickly dissipated so that the remainder of the wheel 101 will be relatively cool. A knife blade 476 is provided in the trailing edge of the wheel 101, intermediate the sides thereof, to slit the sealed tape intermediate the sealed portion thereof, the knife blade 476 being adapted to pass through a slot 477 formed in the lower jaw portion 443 of the upper jaw member 433. A spring biased knife guard 478 is provided in the wheel 101 to shield the knife blade from harm when the trailing edge of the wheel 101 is not in contact with the upper jaw member 433.

The constantly rotating sealing wheel 101 is synchronized to the rest of the structure so that as the envelopes are forced by the crank heads 361 and 361a against the sealing tape, the envelope-holding means 113 will be actuated to pivot in a clockwise direction to hold the lower end of the envelopes. The upper jaw member 443 and the lower jaw members 434 and 436 will then close to clamp the sealing tape around the envelopes and between the jaws. At this time, the sealing wheel 101 will rotate so that its heated leading edge contacts the tape, sufficient pressure being applied to the tape by the spring biased shoe 443 of the upper jaw member 433. The passage of the heated portion of the wheel 101 seals the tape, and the cooler portion of the wheel 101 rotates past the sealed tape joint to cool the sealed tape. The knife blade 476 then severs the sealed portion of the tape, and the upper and lower jaw members are then separated. In the time interval during which both the leading and trailing edges of the sealing wheel 101 are below the level of the envelopes, the crank heads 361 and 361a will move a new bundle of envelopes to the sealing station so that a new cycle of operation may begin.

The bevel gear 98, providing the drive for the sealing wheel shaft 100, is mounted for driving engagement by drive shaft 96 in the following manner. As seen in Fig. 25, drive shaft 96 has a disk 481 mounted loosely thereon, the bevel gear 98 being keyed to the disk collar 482 by key 483. A second disk 484 is keyed against rotation to shaft 96 by key 85. A spring detent assembly 486 mounted on disk 481 engages a radial groove 487 in disk 484. Under normal operation, the drive shaft 96 drives disk 484, this drive being coupled to disk 481 through the spring detent, and thus to the bevel gear 98. If the sealing wheel 101 should be jammed for any reason, the spring detent 486 will be forced out of the groove 487, thereby enabling the drive shaft to continue its rotation without harm to the sealing wheel 101.

Since the sealing wheel 101 is unbalanced on the wheel shaft 100, a counterbalance 488 has been provided on wheel shaft 100 (Fig. 28). A brake shoe 489, mounted on frame 5b, is in contact with the counterbalance 488, with brake material 490 being disposed therebetween.

Means are provided to vary the vertical height of the frame member 5b with respect to frame member 5a, in order that the jaw members and sealing wheel may be adjusted to a position intermediate the top and bottom of the particular envelopes being sealed. As it is desired to use the device on envelopes of a different height, it is desirable to raise or lower the sealing wheel and jaw members so that the tape is sealed at the center of the envelopes.

An adjustment screw 491 (Fig. 6) journaled for free rotative movement in frame 5a, and terminating in a manually operable wheel 492 beneath the machine, extends upwardly through an internally threaded hole 493 in frame member 5b. A second adjustment screw 494 is mounted for free rotative movement on the rear end of frame 5a (Fig. 10) in a similar manner, extending through an internally screw threaded hole 495 in frame member 5b. Chain 496 is trained around a sprocket 497 fixed to adjustment screw 494 and a similar sprocket on adjustment screw 491, so that the two adjustment screws will move in unison. As the manually operable handle 492 is rotated, the adjustment screws 491 and 494 will rotate in unison, carrying the frame member 5b upwardly or downwardly with respect to frame member 5a. Vertical guide members 497 and 497a are fixed to frame member 5a to guide the vertical movement of frame member 5b.

The tape feeding mechanism

In general, the machine uses two rolls of sealing tape, 50 with the tape from one roll being fed to the sealing station from above to provide a band for the upper half of the package of envelopes, and the other roll of tape being fed to the sealing station from below to provide a band for the lower half of the package of envelopes, 55 the two tapes being sealed together on both sides of the package to form the completed band for the package.

In addition, means are provided to unroll the required amount of tape required for each package of envelopes, and means are provided to allow the unrolled tape to be 60 fed freely around the package, the tape being then clamped as the sealing jaws come together, so that a snug fit of the sealing tape around the envelopes is achieved.

Fig. 6 discloses the overall tape feed mechanism. The feed tape 501a, which eventually is fed to the sealing station from above, is supplied from a reel 502 of tape, loosely mounted on shaft 503 carried by frame 5, and passes over roller 504, and roller 505 of the tape-advancing means, then over tape brake roller 506 to the tape 70 guide 507. This tape guide 507 is a U-shaped channel member secured to the right end of frame 5 of the machine and extending upwardly and leftwardly of the machine to a position roughly above the sealing station. The discharge end 507a of the tape guide 507 is secured 75 by bracket 508 to the upright member 249 of frame

5a. The channel member 507 is sufficiently flexible so as to allow the end 507a thereof secured to bracket 508 to be moved laterally with respect to the end 507b thereof fixed to frame 5, as the frame 5a is laterally adjusted with respect to frame 5. A semicircular guide extension 509 is provided on the discharge end 507a of the tape guide 507 to allow the tape 501a to pass downwardly, without sharp bending thereof, to the sealing station.

A leaf spring 511 is fixed to the discharge end 507a of the tape guide to provide a slight pressure on the tape 501a as it passes through the tape guide 507. A vertical rod 512 fixed to the upper jaw arm 432 carries at its upper end a pressure arm 513. The free end of the pressure arm 513 is adapted to move downwardly with the upper jaw and into engagement with the leaf spring 511 to force the leaf spring into strong engagement with the tape 501a. Thus, as the upper jaw 433 descends to engagement with the lower jaws 434 and 436, the tape 501a may pass relatively freely through the tape guide 507 and around the package of envelopes. The pressure arm 513 then bears against the leaf spring 511 to clamp the tape 501a so that the tape is pulled tautly around the envelope package.

The feed tape 501b, which is used to surround the lower half of the envelope package, is supplied from a reel 516 of tape, also loosely journaled on shaft 503, and passes around roller 504, tape-advance roller 505, roller 517, over the tape brake roller 506, forwardly to a curved deflector 518, and upwardly through the tape guide 519 (best illustrated in Fig. 5). The tape guide 519 is an enclosed channel member fixed to frame 5a, through which the tape 501b passes. The upper end of the tape guide 519 is provided with a spring extension 521 to hold the tape against the shaft 81. Shaft 81 has a portion thereof cut away, at 522, registering with the tape 501b, so that when the lower crank arm assembly 352 rotates to carry the envelopes to the sealing station, the cut-out portion 552 of shaft 81 will receive the tape 501b therein to remove the restraining force of spring extension 521 from the tape in order that the tape may pass freely around the envelopes. Shaft 81 then returns to its normal position, causing the spring extension 521 to clamp the tape 501b against shaft 81 as the lower jaw members 434 and 436 move upwardly so that the lower sealing tape 501b is pulled taut around the envelope package.

The manner in which the tape-advancing mechanism operates will now be explained. Returning to Fig. 12, it has been explained that the Z-bar 451 is caused to reciprocate through a full cycle for each cycle of rotation of drive shaft 96. The right end of the Z-bar 451 has fixed thereto a shoe 526 butting against a shoe 527 fixed to rack 114 mounted for reciprocatory movement in rack guide 528, fixed to frame 5. The abutting surfaces of shoes 526 and 527 are sufficiently large so that the shoe 526, which in essence is carried by frame 5b, will exert a longitudinal thrust on shoe 527 carried by frame 5, for all relative positions of frame 5b in respect to frame 5. Rack 114 is in meshing engagement with pinion gear 116 mounted on shaft 117, journaled in frame 5, to translate the reciprocatory motion of rack 114 into oscillatory movement of shaft 117.

Shaft 117 carries at its forward end (Fig. 1) the overrunning clutch assembly 121 for the top brake mechanism, shown in fuller detail in Figs. 24, 26 and 27. Shaft 117 has fixed thereto two collars 531 and 532, the brake-actuating arm 122 being held against collar 531 by a collar 533 slidable on shaft 117 but keyed against rotation thereon. A friction disk 534 is disposed between brake-actuating arm 122 and collar 534, and compression spring 536 forces collar 533 and friction disk 534 against the brake-actuating arm 122. The free end of brake-actuating arm 122 is pivotally fastened to the vertically disposed brake arm 537, which carries a friction brake assembly 538 at its lower end. The brake assembly

538 is provided with a brake shoe 539 adapted to contact tape brake roller 506.

In operation, the shaft 117 will rotate and the friction clutch assembly 121 will cause the brake-actuating arm 122 to rotate with the shaft 117 to move the brake assembly 538 downwardly to clamp the tapes 501a and 501b to the tape brake roll 506. Further rotation of the shaft 117 will merely cause the friction disk 534 to slip, or over-run, in relation to the brake-actuating arm 122. As the shaft 117 reverses its rotation, the friction clutch assembly 121 will cause the brake-actuating arm 122 to move upwardly to release the brake assembly 538 from the tape brake roller 506.

A tape guide bracket 541 is provided between the tape roller 517 and tape brake roller 506, the guide bracket 541 being fastened to frame 5 by arm 542, and being provided with guide pins 543 and 544 to contain the tapes 501a and 501b therebetween.

During the period in which the tapes 501a and 501b are clamped to the tape brake roller 506, the tape-advancing roller 505 is caused to move from the dotted-line position shown in Fig. 6 to the full-line position of that figure, to pull a sufficient amount of tape from the tape reels 503 and 516. The tape-advance roller 505 is moved upwardly to the dotted-line position during the time in which tape is required at the sealing station so that the tape is fed freely to the sealing station.

The operative mechanism for causing such movement of the tape-advancing roller is best seen in Figs. 22, 23 and 6. The tape-advancing roller 505 is rotatively mounted on arm 546, pivotally fastened at its upper end to frame 5. A pivotally mounted link 547 connects the arm 546 to a downwardly depending extension 548 of rack 119 in meshing engagement with pinion gear 118 fixed to shaft 117.

Tension spring 549 attached to rack extension 548 and frame 5 forces the rack to its upward position, and thus urges gear 118 and shaft 117 in a counterclockwise direction, to maintain rack shoe 527 in abutment with the Z-bar shoe 526.

As the machine operates, the completed packages of envelopes 551 are forced into the discharge trough 552 of the machine by the new package coming into the sealing station. The completed package may then be removed from the discharge trough either manually or by conventional automatic means.

From the foregoing, it is apparent that an envelope banding machine has been provided which is capable of forming a band around any desired and predetermined number of envelopes, the band being formed centrally between the sides, and sealed on both sides of the package centrally between the bottom and top of the package. Furthermore, the machine is adapted to form a band in the same manner around envelopes of varying widths and/or heights, by means of simple adjustments readily made by operators of little experience.

Since the machine uses a single power drive source, and since all of the operating mechanisms are driven from the single power drive source, the synchronism of the operating mechanisms is easily accomplished. Once the operating cams have been adjusted to provide the operation set forth in the above description, the machine will operate in a positively synchronous manner, even though the machine is adjusted to accommodate envelopes of varying widths and/or heights.

It is to be understood that the form of my invention, herewith shown and described, is to be taken as a preferred embodiment of the same, and that various changes in the shape, size and arrangement of parts may be resorted to, without departing from the spirit of my invention, or the scope of the attached claims.

Having thus described my invention, what I claim and desire to secure by Letters Patent is:

1. An envelope banding machine comprising a first frame having a magazine extending longitudinally of said

frame and adapted to contain a plurality of uprightly stacked envelopes, counting means on said first frame adapted to count said envelopes one by one from said magazine, a second frame mounted on said first frame and adapted to be transversely adjustable to said first frame, transfer means mounted on said second frame adapted to transfer a predetermined number of said counted out envelopes from said magazine to a banding station, a third frame mounted on said second frame and adapted to be vertically adjusted with respect to said second frame, means to encircle said envelopes at said banding station with a band of tape, jaw means mounted on said third frame to clamp said encircled tape around said envelopes, a sealing means mounted on said third frame to seal said clamped tape, and means to operate each of said counting means, transfer means, jaw means and sealing means from a common power drive source.

2. In an envelope banding machine, a magazine having side walls adapted to receive a plurality of uprightly stacked envelopes therebetween, an endless feed belt on each of said side walls adapted to contact the side edges of said envelopes, means at the discharge end of said magazine to count the envelopes out of said magazine one by one, a rotatable drive shaft, means responsive to the rotation of said drive shaft to operate said counting means, and means responsive to rotation of said drive shaft to intermittently operate said feed belts to urge said envelopes towards said counting means.

3. In an envelope banding machine, a storage magazine adapted to store a plurality of envelopes therein, a continuously rotating helical wheel at one end of said magazine to count envelopes from said magazine one by one, a sucker rod mounted below said magazine and having a sucker head adapted to engage the forward surface of an envelope counted out of said magazine by said wheel, means to move said sucker rod in a generally rectangular path upwardly into engagement with said envelope, forwardly from said magazine, downwardly below said magazine and rearwardly towards said magazine, a source of vacuum, and means to connect said vacuum source to said sucker head during said forward travel of said sucker rod, whereby said counted out envelope is pulled from said magazine by the sucker rod during the forward movement thereof.

4. In a device as set forth in claim 3 further including means responsive to the failure of said sucker head to engage a counted out envelope to discontinue the operation of said wheel and said sucker rod moving means.

5. In an envelope banding machine, a magazine adapted to contain a plurality of envelopes therein, counting means to count said envelopes out of said magazine one by one and to move said counted out envelopes to a first position, a first continuously rotatable drive shaft, means responsive to rotation of said drive shaft to actuate said counting means, means to transfer said counted out envelopes from said first position to a second position, said transfer means including a picker bar mounted generally below said magazine, a second continuously rotatable drive shaft, means responsive to the rotation of said second drive shaft to move said picker bar in a generally rectangular path so that the picker bar moves upwardly between said magazine and said first position, then away from said magazine to said second position, then downwardly, and then towards said magazine, and gear means to transmit rotative movement of said first drive shaft to said second drive shaft to cause said transfer means to perform one cycle of operation in the period in which said counting means counts out a predetermined number of envelopes.

6. In an envelope banding machine having an envelope storage magazine and a banding station, counting means at one end of said magazine to continuously count said envelopes from said magazine one by one, a picker bar mounted on said machine below said magazine, and means to move said picker bar in a generally rectangular path

upwardly between said magazine and said counted out envelopes, forwardly from said magazine toward said banding station, downwardly below said magazine and rearwardly toward said magazine, whereby said counted out envelopes are moved from said magazine toward said banding station by the forward movement of said picker bar and said picker bar returns to its starting position below said envelopes.

7. In a device as set forth in claim 6 further including a first power drive means for operating said counting means, a second power drive means for operating said picker bar, and means for synchronizing said first and second drive means to cause said picker bar to move through one rectangular movement in the time that said counting mechanism counts out a predetermined number of envelopes.

8. In an envelope banding machine having a banding station adapted to receive a group of envelopes to be banded, means to pass a band of sealing tape around one side of said envelope group and opposite side edges thereof, a pair of jaw members mounted in said machine, means to move said jaw members together at the mid point of said envelope group on the side opposite said one side thereof, said jaw members being adapted to clamp the encircling ends of said tape therebetween, one of said jaw members having spaced parallel faces, a sealing wheel mounted for rotation in a plane parallel and between said spaced faces, the other of said jaw members having a shoe intermediate the faces thereof adapted to contact said wheel, and spring means urging said shoe in contact with said wheel.

9. In a device as set forth in claim 8 in which said sealing wheel is provided with a knife member extending radially from the outer surface thereof and between the sides thereof, and said shoe is provided with a slot to receive said knife member.

10. In an envelope banding machine having a set of clamping jaw members movable into engaging relation with one another, said jaw members being mounted for reciprocal movement on the frame of said machine, a drive shaft journaled for rotation in said frame, a cam mounted on said drive shaft, a first lever having one end pivotally connected to one of said jaw members and the other end in engagement with said cam, said first lever being pivotally mounted intermediate its ends to one end of a second lever, said second lever being pivotally mounted intermediate its ends to said frame, spring means connected to the other end of said second lever and said frame to restrain relative movement therebetween, and means to move the other of said jaw members in an equal and opposite amount to the movement of said one jaw member.

11. In an envelope banding machine in which groups of envelopes are moved from a storage magazine to a banding station, a sealing wheel mounted for rotation in said machine and having its axis of rotation parallel to and offset from the line of movement of said envelopes, said sealing wheel having a portion of its circumference cut away whereby when said cut away portion of said wheel is adjacent said line of movement, said groups of envelopes may pass unimpeded by said wheel, heating means in the leading edge of the uncut portion of said wheel to heat the outer circumference thereof, means to cool the trailing edge of said uncut portion of said wheel, and knife means extending radially of said uncut portion from the circumference thereof and intermediate the sides thereof.

12. In an envelope banding machine having a storage magazine from which groups of envelopes are adapted to be counted from said magazine and a sealing station, transfer means to carry said groups of envelopes from said magazine to said sealing station, clamping jaw members on opposite sides of the path of travel of said envelope groups, means synchronized with the movement of said transfer means to move said jaw members into

engagement with one another after said transfer means have moved said envelope groups to said sealing station, a finger mechanism adapted to hold said envelope groups in said sealing station, and means synchronized with the movement of said transfer mechanism and said jaw members to actuate said finger mechanism into holding position after said transfer means have carried said envelope groups to said sealing station and before said jaws move into engagement with each other.

13. In an envelope banding machine having an envelope storage magazine and a banding station, counting means at one end of said magazine to continuously count said envelopes from said magazine one by one; a picker bar mounted on said machine below said magazine, means to move said picker bar in a generally rectangular path upwardly between said magazine and said counted out envelopes, forwardly from said magazine toward said banding station, downwardly below said magazine and rearwardly toward said magazine; a clamp bar pivotally mounted on said machine below said magazine and at a distance below said magazine less than the length of said clamp bar, said clamp bar being normally rotated about its pivotal mounting away from said magazine to a normal position whereby all of said clamp bar is below said magazine, means to rotate said clamp bar upwardly and towards said magazine as said picker bar is moved upwardly, whereby said counted out envelopes are held between said picker bar and said clamp bar, and means to return said clamp bar to its normal position in response to forward movement of said picker bar, and whereby said counted out envelopes are moved from said magazine toward said banding station by the forward movement of said picker bar and said picker bar returns to its starting position.

14. In an envelope banding machine, an envelope storage magazine adapted for receiving a stack of envelopes and guiding said envelopes toward a counting station, counting means for removing envelopes one by one from said stack and placing each in a counted pile against a kick-out member, said kick-out member being operably movable into and out of the guided path, transfer means for moving a counted pile of said envelopes to a banding station, first actuating means for operating said kick-out member out of engagement with said counted pile, second actuating means for operating said transfer means, said first and second actuating means being synchronized to operate said kick-out member out of engagement with said counted pile shortly before said transfer means is operated and causing said kick-out member to be operated into the envelope guided path shortly after said transfer means is initially operated.

15. An envelope banding machine comprising a first frame having an envelope storage magazine extending longitudinally of said frame and adapted to contain a plurality of uprightly stacked envelopes, counting means to count envelopes out of said storage magazine into a counted pile; a second frame mounted for being transversely laterally adjusted with respect to said first frame, transfer means mounted on said second frame to move said counted pile to a banding station, said transfer means being laterally adjustable with respect to said magazine to accommodate varying sizes of envelopes; a third frame mounted for being transversely adjusted both vertically and horizontally with respect to said first frame, means to encircle said counted pile of envelopes at said banding station with a band of tape including jaw means mounted on said third frame to clamp said encircled tape around said counted pile and a sealing means mounted on said third frame to seal said clamped tape, said jaw means and said sealing means being horizontally and vertically adjustable to accommodate varying sizes of envelopes.

16. A device as set forth in claim 15 further including a continuous power drive source, a first drive means to connect said power drive source to said counting

means, a second drive means to connect said power drive source to said transfer means, said second drive means being synchronized to said first drive means to cause said transfer means to complete one cycle of transfer operation during the time said counting means counts out a predetermined number of envelopes, and a third drive means to connect said power drive source to said jaw means and said sealing means, said third drive means being synchronized with said second drive means to cause one cycle of operation of said encircling means for each cycle of operation of said transfer means.

5 17. In a device as set forth in claim 16 further including a banding tape feeding means to supply tape to said encircling means, and means operable by said third drive means to form a slack loop of tape to be fed to said encircling means for each cycle of operation thereof.

10 18. In an envelope banding machine, a storage magazine adapted for receiving a stack of envelopes, a continuously rotating helical wheel at one end of said magazine to count envelopes from said magazine one by one, a sucker rod having a sucker head adapted to engage the forward surface of an envelope being counted out of said magazine by said wheel actuating means to move said sucker head in a cyclical path into engagement with 15 said counted envelopes, then away from said magazine and out of engagement with said envelope, a source of vacuum, and conduit means to connect said vacuum source to said sucker head during the envelope engaging portion of said cyclical path movement, whereby said counted out envelope is pulled from said magazine by the movement of said sucker head.

19. In a device as set forth in claim 18 and further including motor drive means for said banding machine, and means responsive to a failure in suction pressure in said sucker head during the letter engaging portion of its cycle for de-energizing said motor drive means, thereby discontinuing operation of said machine.

20 20. In a device as set forth in claim 18 including a motor drive means for the driven apparatus of said machine, an energizing circuit for said motor drive means including a solenoid operated switch means, and an energizing circuit for said solenoid operated switch including a pressure sensitive switch connected to said conduit means in series with a cam operated cycle-detecting switch, whereby the failure of said sucker head to engage 25 a counted out envelope will cause said motor drive means to be de-energized.

21. In an envelope banding machine, a storage magazine adapted for receiving a stack of envelopes, a continuously rotating counting wheel at one end of said magazine to count envelopes from said magazine one by one, a pair of sucker rods each having a sucker head adapted to engage the forward surface of an envelope being counted out of said magazine by said wheel, means to move said sucker heads in cyclical paths into engagement with said counted envelope, then away from said magazine and out of engagement with said envelope, said sucker heads being moved out of cyclical phase with each other, whereby only one sucker head operates upon a counted envelope at a time, a source of vacuum, and means to connect said vacuum source to said sucker heads during the envelope engaging portion of each sucker head movement, whereby counted out envelopes are pulled from said magazine alternately by said sucker heads.

65 22. In an envelope banding machine, a magazine adapted to contain a plurality of envelopes therein, counting means to count said envelopes out of said magazine one by one and to move said counted out envelopes to a first position, a first continuously rotatable drive shaft, means responsive to rotation of said drive shaft to actuate said counting means, means to transfer said counted out envelopes from said first position to a second position, said transfer means including a picker bar, a second 70 continuously rotatable drive shaft, means responsive to

75

the rotation of said second drive shaft to move said picker bar in a generally rectangular path so that the picker bar moves between said magazine and said first position, then away from said magazine to said second position, then from between said first and second positions, and then towards said magazine, and gear means to transmit rotative movement of said first drive shaft to said second drive shaft to cause said transfer means to perform one cycle of operation in the period in which said counting means counts out a predetermined number of envelopes.

23. In an envelope banding machine, a magazine adapted to contain a plurality of envelopes therein, counting means to count said envelopes out of said magazine one by one and to move said counted out envelopes to a first position, a first continuously rotatable drive shaft, means responsive to rotation of said drive shaft to actuate said counting means, means to transfer said counted out envelopes from said first position to a second position, said transfer means including a picker bar, and a clamp bar, a second continuously rotatable drive shaft, means responsive to the rotation of said second drive shaft to move said picker bar in a generally rectangular path so that the picker bar moves between said magazine and said first position, then away from said magazine to said second position, then from between said first and second positions, and then towards said magazine, means synchronized with the movement of said picker bar between said magazine and said first position for moving said clamp bar toward said picker bar and yieldably clamping said counted out envelopes, and gear means to transmit rotative movement of said first drive shaft to said second drive shaft to cause said transfer means to perform one cycle of operation in the period in which said counting means counts out a predetermined number of envelopes.

24. In an envelope banding machine having an envelope storage magazine and a banding station, counting means at one end of said magazine to continuously count said envelopes from said magazine one by one, means to transfer a pile of counted envelopes from said magazine to said banding station including a picker bar and a clamping bar; means to move said picker bar in a generally rectangular path between said magazine and said counted envelopes, forwardly from said magazine toward said banding station, from between said envelopes and said magazine, and then towards said magazine; means synchronized with the movement of said picker bar be-

tween said magazine and said counted envelopes for moving said clamp bar toward said picker bar and yieldably clamping said counted envelopes; whereby said counted out envelopes are moved from said magazine toward said banding station by the forward movement of said picker bar and said picker bar returns to its starting position below said envelopes.

25. In an envelope banding machine having a counting station and a banding station, means to transfer a predetermined number of envelopes from said counting station to said banding station, tape feeding means situated at opposite sides of the path of travel of said envelopes being transferred, said tape feeding means being adapted to supply a strip of banding tape across said path of envelope travel, said transfer means being adapted to carry said envelopes to said strip of banding tape and to force said envelopes and tape forwardly to said banding station, oppositely movable and reciprocating jaw means at said banding station to close together on the rearward side of said envelopes to force said banding tape around said transferred envelopes and to clamp said tape, a tape braking means adapted to be actuated from a tape releasing position to a yieldable clamping position, brake actuating means synchronized with the movement of said jaw means to its closed position to operate said brake means, thereby forming a taut band of tape around said transferred envelopes when said jaw means are closed, further including a rotary sealing wheel, said wheel having a peripheral edge for engaging said tape as it is clamped by said jaw means, and means for rotating said wheel in synchronism with movement of said jaw means.

26. In a device as set forth in claim 25 and further including means synchronized with the movement of said jaw means to sever said sealed tape intermediate the ends of the sealed portion.
